Primary Examiner — Elizabeth Albert*(74) Attorney, Agent, or Firm* — Howard C. Miskin; Gloria Tsui-Yip(57) **CLAIM**

The ornamental design for an instrument barrel, as shown and described.

DESCRIPTION

FIG. 1 is a perspective view of my new design;

FIG. 2 is a front elevational view thereof;

FIG. 3 is a rear elevational view thereof;

FIG. 4 is a right side view thereof;

FIG. 5 is a left side view thereof;

FIG. 6 is a top view thereof; and,

FIG. 7 is a bottom view thereof.

The broken lines showing the writing tip housing in FIGS. 1-5 and 7 and the features on the push button in FIGS. 1, 2, 4, and 5 are included for the purpose of illustrating portions of the instrument barrel that form no part of the claimed design.

1 Claim, 4 Drawing Sheets*FIG. 2*
